UNITED STATES PATENT OFFICE

JOSEPH JOHN STOETZEL, OF QUEENS VILLAGE, NEW YORK, ASSIGNOR TO G & G
ATLAS SYSTEMS, INC., OF NEW YORK, N. Y., A CORPORATION OF NEW YORK

BLOWER

Application filed December 27, 1926. Serial No. 157,182.

This invention relates generally to centrifugal fans or blowers.

There are three different classes of centrifugal blowers differently designed to suit the requirements of different classes of work to be performed, but all partaking in common of similar basic characteristics and governed by the same operating principles. One of these classes is the pressure blower in which free atmospheric air is compressed to the desired degree before reaching the discharge outlet, the compressed air being discharged at the outlet at a velocity equal to the peripheral velocity of the rotor.

Another class is the so-called "booster" blower in which the blower is inserted intermediate the ends of a conveying duct, as in transferring gas from one storage tank to another. The booster blower may be supplied with a filling stream having a density equal to or greater than that of the atmosphere and may operate to compress and propel, or merely to propel, the stream of gas passing therethrough.

The third class is the evacuating blower in which the filling stream of air is supplied at a density below that of the atmosphere, the blower operating to compress the mass of air to the required density and to discharge the air into atmosphere.

It has been the standard practice among different blower and fan manufacturers to make use of substantially the same formulas or ratios with respect to the sizes and relationship of parts, and generally speaking the blower constructions heretofore provided have operated with a relatively low efficiency. An example of a standard prior construction is a pressure blower having a double fan wheel of twenty-seven inches diameter with intake openings in each side of the casing of thirteen and one half inches in diameter, or one half the diameter of the wheel. In this particular form of standard construction the fan wheel is provided with eighteen vanes spaced equally distant from each other. The vanes have a width at the intake end, (i. e., at the inner end), equal to twenty-five per cent of the diameter of the wheel and a width at the discharge or outlet

end equal to twelve and one half per cent of the diameter of the wheel.

With this particular structural arrangement, (similar inefficient arrangements being characteristic of other sizes and types of prior constructions), it will be seen that, since the vanes are separated at their tip or discharge ends by substantially double the distance separating the vanes at their intake ends, and the width of the vanes at the intake ends is substantially double the width at the discharge ends, the cross sectional areas of the intake openings are substantially the same as the cross sectional areas of the discharge openings. The result is that the moving column of air in a channel between the vanes is not compressed as it approaches the discharge outlet, since the column is moving through a channel of unchanging or substantially unchanging cross section with a constantly increasing velocity. It will be evident that this condition necessarily produces a rarefaction or expansion of the air column. In addition the relatively great peripheral separation of the discharge ends of the blades permits of the formation of a partial vacuum immediately to the rear of the moving blades and this partial vacuum has the effect of still further rarefying or attenuating the moving stream of air.

The result is that there can be no compressing of the stream of air advancing toward the discharge ends of the blades. Instead, there is a rarefaction with an accompanying objectionable back lashing effect caused by a rush of air from the housing into the partial vacuum formed in discharge ends of the spaces between the blades with a consequent loss of efficiency brought about through the rehandling of a portion of the discharged air. The objectionable back lashing is very apparent in the operation of prior blowers of the pressure types, in which the outlet of the housing is arranged to restrict the discharge to produce the desired pressure effect.

A general object of the present invention is to provide a blower construction of the centrifugal fan type which will be free from the objectionable features referred to and which will operate with a substantial increase in

efficiency as compared with the efficiency of blower constructions heretofore known and used.

The invention comprises a centrifugal blower construction in which a relative arrangement of vane areas, intake openings, discharge openings, number of vanes, length of vanes and other factors are so chosen as to cause the apparatus to operate at a relatively high degree of efficiency with relation to the expenditure of power required for operation. More specifically, I so design the blades in their proportioning and relation to each other that the air streams passing through the channels from the intake openings of the blades to the discharge ports thereof do not undergo rarefaction or expansion in any degree, but, on the contrary, decrease in cross-sectional area with the result that the streams emerge at the discharge ports of the vanes with the density of the mass of air fully restored and even increased, and having had a velocity of travel imparted thereto which is exactly equal to the peripheral speed of the rotating wheel.

Other features of the invention will be hereinafter referred to.

In the drawings, in which one of many possible embodiments of the invention has been selected for illustration:

Fig. 1 is a view partly in front elevation and partly in vertical section of a blower of the pressure type embodying the invention;

Fig. 2 is a view in side elevation and partly in section of the device shown in Fig. 1.

Referring to the drawings for a more detailed description of the invention, a blower of the centrifugal type is shown in which a double rotor or fan wheel 10 is mounted on a shaft 11 for rotation in a casing or housing 12. The shaft 11 is journaled at 13 in the upper ends of suitable standards 14 and is provided with a driving pulley 15 in a known manner.

The double fan wheel is provided with hub bracket members 16 having radially extending flange portions 17 between which is clamped an annular web or frame piece 18 to which are riveted the inner edges of a series of fan blades 19. A scroll-shaped housing 20 is mounted on the peripheral portion of the housing 12 and is provided with a discharge port at 21 through which air is discharged from the blower into the manifold or conduit provided therefor. The discharge housing is so constructed as to restrict the discharge therefrom to a degree sufficient to produce the desired pressure therein, the compressed stream emerging at the outlet at a velocity equal to the peripheral velocity of the wheel.

The vanes or blades 19 are arranged in a relatively slightly spaced apart relation as compared with the arrangement of blades in blowers heretofore known and used. For example, in a fan wheel of twenty-seven inches

in diameter, the size chosen for example and comparison, I find that the greatest efficiency is attained when forty-two blades or vanes are used, the separation of the blades at their discharge ends 21 being two inches, while the intake ends 22 of the blades, which are at a distance of six and three-quarter inches from the axis of rotation, are separated by a distance of only one inch.

The inlet opening 23, which is supplied at either side of the double wheel, has a diameter equal to one-half the diameter of the wheel in the particular example shown.

An important feature of the invention resides in the design of the blades which are, in the example shown, 6.75 inches wide at their intake end, measured between their widest points 22 at the junction of the blades with the edge of the inlet opening 23. The width of the discharge ends of the blades at 21 is, in the example shown, 1.7 inches, so that the width of the blades at the intake end is substantially four times the width of the blades at the discharge end. With this proportioning of the vane areas and distances separating the individual blades, it will be seen that the channels between the blades have a cross sectional area of one times 6.75 or 6.75 square inches at their intake ends while at their outlet ends the same channels have a cross sectional area of two times 1.7 or 3.4 square inches. In other words, the cross sectional area of the intake ends of the channels is substantially twice the cross sectional area of the discharge or outlet ends.

With this arrangement of structure it will be seen that the density of the air streams moving through the channels formed between the vanes is so regulated that the initial loss in density at the points of entry of the air into the channels and the tendency to further loss due to the increasing velocity of flow are wholly compensated for. The effect of this is to restore or rebuild and to maintain the density of the air streams at substantially that of the atmosphere so that when the air streams emerge at the outlet ports 21 their density has not been impaired but, on the contrary, there is imparted to the air streams the necessary pressure to establish a velocity of flow equal to that of the peripheral speed of the wheel.

This useful arrangement which prevents the back lashing of air referred to with its attendant loss of efficiency and at the same time does not restrict the area of the outlet ports beyond that necessary to impart to the flowing stream the necessary velocity and normal density, delivers the air into the housing for restriction therein to produce the desired pressure effects.

In order to more specifically compare my improved blower with a typical structure of the prior art, a standard prior art blower having a fan wheel diameter of 27 inches with

an inlet port of 13 inches diameter at each side, and with 18 vanes 6.75 inches wide at the intake end and 2.875 inches wide at the discharge end, is taken as a basis for comparison.

A standard type prior art blower having the dimensions and number of vanes referred to and operated at a peripheral speed of 16,000 feet per minute, will deliver per minute into the enclosing shroud or housing approximately 5,720 cubic feet of air. Since the blowers under consideration are of the pressure type, it is necessary to produce a pressure effect in the mass of air delivered from the passages of the blower wheel into the housing. This pressure effect is ordinarily produced by restricting the free passage of air from the housing by means of an appropriate restriction in the size of the housing discharge port. In the particular blower construction chosen for comparison a restriction of 39 per cent is produced in the volume of air passing through the housing thereby producing an ultimate discharge volume of 3,490 cubic feet per minute.

The prior art blower, thus described, is to be compared with a blower of applicant's type having a fan wheel of the same diameter, 27 inches, and rotating at the same peripheral speed, 16,000 feet per minute. Applicant's blower is provided with 42 vanes, as compared with 18 vanes in the prior art structure, the vanes having a width at their intake ends of 6.75 inches and a width of 1.7 inches at their discharge ends. A blower having this relationship of parts will deliver 7,854 cubic feet of air into the housing per minute, as compared with 5,720 cubic feet delivered by the prior art machine. A restriction of 43 per cent placed upon this volume, to produce the pressure conditions required, reduces the volume to 4,577 cubic feet per minute, this volume of air being handled at a saving of 25 to 33.3 per cent in horsepower as compared with the power required to operate the standard blower construction of the prior art. In other words, my improved blower, as compared with prior blower constructions, move a greater volume of air, at a higher density, and without a proportionate increase in the input of power.

This substantial increase in efficiency of applicant's blower over the blowers known in the prior art is due to the elimination of back lash and other difficulties encountered by the rarefaction of the air stream which occurred in the channels formed between the particular blades typical of the prior art. Not only did back lash effects occur because of the rarefaction due to the lack of proper convergence of the delivery channels but also, and in a considerable degree, because of the excessive spacing apart of the vanes or blades which made up the fan wheel structure. As has already been pointed out, the excessive spacing

of the blades aided in the production of partial vacuum effects immediately to the rear of each blade tip and this partial vacuum condition was an important factor in producing the objectionable back lash effects referred to through the added expansion or rarefaction of the air streams approaching the discharge ports.

While the characteristics of a typical pressure blower have been given, a proportioning of blade areas to provide an improved efficiency in blowers of the "booster" type can also be readily achieved. A blower of this construction is placed within a conveying duct and since the kinetic energy expended in filling the intake side of the wheel is convertible into useful work through assisting the velocity of flow through the duct, a blower of this type will operate at its best efficiency when the kinetic energy expended in filling the wheel and propelling and compressing energy exerted by the wheel on the volume of air passing therethrough are equivalent to each other. This ratio can be best established when the diameter of the inlet opening in the "booster" blower is seventy per cent of the diameter of the wheel. With this proportioning of the inlet opening of the blower to the diameter of the wheel, a capacity of 2.6 times the capacity of a blower constructed with an intake opening of fifty per cent of the diameter of the wheel is obtained.

When operating as an evacuating blower, the structure has two duties to perform, that is, the establishing of a filling stream of air at a density below that of the natural atmosphere and the compressing of the air passing through the structure to the required density and discharging the air, thus compressed, into the natural atmosphere. The air handling capacity of a blower of this type is limited to the area of the discharge ports at any given peripheral velocity and the capacity to fill the channels at the outlet ports is determined by the degree of rarefaction of the air to be handled. With these considerations in mind, the length and width of the vanes can be properly proportioned to secure efficient results irrespective of the degree of rarefaction of the air to be handled.

The invention is not confined to use with double fan wheel structures but similar improvements in design and efficiency of operation can be as readily accomplished in fan wheels of the single inlet type. It will be clear that the inlet barrel of a single inlet wheel must have double the depth of either inlet barrel of a double inlet wheel of the same size in order to cause the single inlet wheel to operate at the same capacity as that of the double wheel.

It will be seen that a type of blower construction has been developed in which the number and areas of the vanes have been calculated in strict proportion to the volume

of air to be handled while the outlet ports have areas just sufficient to permit the volume of air to be delivered at a velocity equal to the peripheral velocity of the wheel. It will be clear that the diameter of the inlet openings may be varied in accordance with the work to be done and that the peripheral speed of the wheel will be increased to compensate for the shorter length of the vanes when the diameter of the inlet opening is increased.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:—

1. In a blower of the centrifugal type, a fan wheel having radially extending vanes whose number is such and whose areas are so proportioned to the speed of rotation of the wheel and to the volume of the air flow as to cause the air passing through the outlets of the fan wheel to travel at a velocity equal to the peripheral velocity of the wheel.
2. In a blower of the centrifugal type, a fan wheel having radially extending vanes in which the ratio of the widths of the outlet ends of the vanes to the widths of the inlet ends is such that the air passing through the outlets is compressed sufficiently to produce a velocity of flow therein equal to the peripheral velocity of travel of the outlet end of the vanes.
3. In a blower of the centrifugal type, a fan wheel provided with radially disposed channels, whose cross-sectional areas decrease outwardly, the area at different points being inversely proportional to the radial distance from the axis of rotation.
4. In a blower of the centrifugal type, a fan wheel provided with radially disposed channels, the area at the exit end of the channels being one-half the area at the admission end thereof.
5. In a blower of the centrifugal type, a rotatable fan wheel having side members and transverse vanes forming radial channels, the side members converging outwardly toward each other at such an angle that the area of the channels is inversely proportional to the radial distance from the axis of rotation, substantially as described.

JOSEPH JOHN STOETZEL.
